UNITED STATES PATENT OFFICE.

GUSTAVE O. DEGENER, OF BROOKLYN, NEW YORK, ASSIGNOR TO ROYAL TYPEWRITER COMPANY, INC., OF NEW YORK, N. Y., A CORPORATION OF NEW YORK.

ADDING ATTACHMENT FOR TYPEWRITING MACHINES.

Original application filed March 9, 1925, Serial No. 14,315. Divided and this application filed August 14, 1925. Serial No. 50,262.

This application is a division of my application Serial No. 14,315, filed March 9, 1925.

One of the objects of the invention disclosed and claimed in said parent application was an error check mechanism which should prevent the occurrence of an error when the total is copied from the column totalizer and entered into the grand totalizer or if such error should be made would 10 immediately call attention of the operator thereto. Two forms of this mechanism were disclosed in one of which a complete depression of the wrong key was prevented and in the other of which the wrong key could 15 be depressed but would be prevented from returning to normal position. The parent application contains claims generic to both forms and claims specific to the first form. The claims of this application are intended 20 to be specific to the second form of error check mechanism wherein the key may be depressed but the operator is immediately notified that an error has been made.

Reference is had to the parent case for 25 a disclosure of the general structure of the adding attachment and the details thereof, the illustration and specification of this case being merely sufficient to show clearly and completely the form of error check mechanism claimed herein.

In the drawings:

Figure 1 is a longitudinal section showing the error check mechanism and such other elements of the computing mechanism as are 35 necessary to show the relative position and cooperation of the error check mechanism with the remainder of the machine.

Figure 2 is a top plan view of the error 40 check mechanism.

Figure 3 is a transverse section on the line 3—3 of Figure 2.

Figure 4 is a transverse section of a portion of the mechanism showing the means for bringing the error check mechanism into 45 operative condition by the movement of the totalizer.

The travelling register a portion of which is designated at A in Figure 1 comprises a column totalizer, a portion of which is 50 shown at B in Figure 4, and a grand total-

izer which has not been illustrated herein. This travelling register comprises transverse connecting bars 8 and 10 and travels on rods 12 and 13. These connecting bars and rods are connected to side plates 2 and 3 of the frame. The whole is enclosed by a casting C. Each of the totalizers is of the usual type and includes a train of mechanism actuated from the numeral keys of the typewriter in the usual or desired manner. A series of rock shafts 20 underlie the typewriter key board and also a portion of the adding attachment and are connected to the typewriter key levers by links 22 which are pivoted to arms 21 rigid on one end to the rock shafts. To the other ends of the rock shafts are connected arms 23 which are pivoted to sliding members 24 which operate the trains of adding mechanism.

The transverse member 10 supports a sheet 70 metal member 27 which has its lower end slotted into a series of fingers and bent to form a substantial cylinder 28. Balls 29 are placed in the cylinder and are held by stops at the end thereof so that there is 75 just enough play to permit the passage of a depending projection 30 on one of the bars 24 between two of the balls. When one key is depressed and its connected bar 24 is moved until the projection 30 passes between 80 two of a series of balls 29, it is impossible to depress another key lever at this time.

In an attachment of this type as is more clearly set forth in the parent application, the items are written one by one in a column 85 and recorded in the column totalizer. When it is desired to write the total the register is moved to a position which brings the grand totalizer into the computing zone and therefore in operative relation with the master wheel. The total is then copied from the column totalizer and set up in the grand totalizer, no change in the condition of the column totalizer being made at this time. The error check mechanism comprises devices 90 which are thrown into operative relation by the movement of the register which brings the grand totalizer into the computing zone and said error check devices in the present form of the invention permit 100

the depression of an incorrect key when the total is being copied but locks said key against return movement. The operator is therefore notified that an error has been 6 made and may correct this error before proceeding with his work.

This mechanism will now be described in detail. A projection 181 (Figures 1 and 4) on the travelling register contacts with a 10 roller 182 as the register moves to the left to bring the column totalizer out of the computing zone and the grand totalizer into said zone. This roller 182 is carried by one arm 183 of a bell crank lever pivoted at 184 15 to a bracket on the frame member 2 and having a downwardly extending arm 185 normally drawn in one direction by a spring 186 attached to a stud 187 projecting from said frame. A stop 188 limits the movement 20 of the bell crank lever under the influence of this frame. The arm 185 is connected by a link 189 to a lever 190 which is pivoted at 191 to a frame member. This lever has a hook 192 normally underlying a lever 193 25 (Figures 1 and 4). When this hook is moved out of engaged relation with the lever 193 the latter moves counterclockwise about its pivot due to the weight of the longer arm thereof and also due to the tension of the 30 spring 242.

A rocking frame 239 is mounted on a shaft 240 which is pivoted in the frame plates 2 and 3 and this frame is normally drawn in one direction by a spring 241. The ends of 35 the sliding bars 24 normally contact with such rocking frame 239 at all times so that the frame is moved each time a key is depressed. The spring 241 therefore acts as a return spring for all of the sliding bars 24 40 and the train of mechanism connected thereto.

When the lever 193 is released from its latch and drops under its weight and the tension of the spring 242, the downwardly moving 45 end of the lever engages an arm 243 of a bell crank lever pivoted at 244 on a bracket 245 carried by the frame plate 3. The depending arm 246 of this bell crank lever has a rounded end lying between the sides of a U-shaped bearing 247 of a crank 248 which is slidable 50 on the shaft 240. This crank has a jaw 249 which engages the rock frame 239 when said crank is moved to the left. Thereafter the frame 239 and the crank 248 will move together whenever the frame is rocked by the depression of a numeral key. It is to be remembered that at this time the grand totalizer is in the computing zone.

A coil spring 250 within which lies a stop 60 plunger 251 connects the upper end of the bell crank 248 with a crank arm 252. This crank arm is integral or rigid with a sector shaped cam member 253. The locking sectors 254 are all made with a slot through 65 which passes a lug 267 on the sliding bars

24. The sectors as well as the crank 252 are positioned on the shaft 255 being spaced by collars and held rigidly by nuts at each side thereof. This shaft is mounted between the side plates 2 and 3 to allow for slight endwise movement in order to throw the same into and out of operative position. The side movement of this shaft with its sectors is controlled by a lever 257 which is connected by a wire link 256 to the bell crank lever 70 246 so that both of these parts are always moved together but in opposite directions. That is to say, when the jaw 249 on the lever 246 is disconnected from the rocking frame 239 the rock shaft 255 with all of its rocking 75 sectors thereon is also in disengaged position.

There is employed in each train of computing mechanism a series of gears 216 each of which is provided on its face with a pair of projections 217. A digit feeler 214 which is 80 mounted on the transverse member 10 is connected by a link 213 to one of the sectors 254. It is mounted to slide the extent of one space on its shaft 220 and is drawn to the right to hold it normally in correct alignment by a 85 spring 258 attached thereto and to the frame plate 3. It is stopped and aligned in this position by sheet metal bracket 259 carried by the frame member 11.

A disconnect key 260 is pivoted at 261 to 90 frame member 3 and has a link 262 connecting it to the member 66 (see Figure 2). This member 66 is engaged by the travelling register when the latter is in home or extreme right hand position so as to produce 100 the same result as is produced by the depression of the disconnect lever by hand so that when the register is in home position the error check mechanism is inoperative and does not affect the depression of the numeral 105 keys.

Pivoted on a bracket 263 is a bell crank lever one arm 264 of which projects outwardly through the opening in the frame member 3 and underlies the disconnect 110 key lever. The other arm 265 extends downwardly and bears against the cam 253 which is also fast on the shaft 255 and in this manner the disconnect key moves the sectors to inactive position. The lever 193 is provided with an offset extension 266 underlying the arm 243 of the bell crank lever so that the movement of the lever 193 in either direction will operate this bell 115 crank lever and effect connection or disconnection between the frame 239 and the locking sectors. Projecting ears 267 on the slide bar 24 are right angular in shape as shown in Figure 2, having an inclined face 268 and a straight face 269. These ears engage a stop rod 270 to limit the return movement of the parts.

The lever 193 is shown as provided with two extending arms 237 and 238. The arm 237 is operated by mechanism described in 120 125 130

the parent case for returning the lever 193 into position where it is controlled by the latch 192 when the carriage is moved to the right. Projection 238 extends through the casing and may be manually actuated to produce the same result whenever desired. These features form no particular part of the present invention and are therefore not described in further detail.

10 The operation may be described briefly as follows: When items are being written and entered in the column totalizer, the rocking frame 239 is disconnected from the error check mechanism and the projections 267 on 70

15 the slide bars 24 move freely to the right of the lock sectors. As soon as the grand totalizer is brought to the computing zone and the lever 193 released as before described, the bell crank pivoted at 244 is operated to effect a lateral as well as a rotative connection between the rocking frame 239 and the lock sectors 254 carried by the shaft 255. The depression of any numeral key will now oscillate the shaft 255 and operate the 75

20 digit feeler. If the digit feeler is stopped early in its movement, the spring 250 will permit the continued movement of the rocking frame 239. The slots in the sectors 254 are arranged in stepped relations one corresponding to each digit from 0 to 9. Each 80

25 key can be depressed without operating the error check mechanism only when the slot in the corresponding sector is in line with the projection 267. If the correct key is operated, this projection 267 will pass through the corresponding slot in the lock 85

30 sector 254 and return therethrough without interference. However, if an incorrect key is depressed, the projection 267 will not meet a slot in the corresponding lock sector and the inclined face 268 of this projection will engage the side of the lock sector and cam it to the left against the spring 242, thus allowing the continued movement of the 90

35 slide bar 24 and consequently a complete depression of the key lever. As soon as the projection 267 has passed the lock sector upon the downward movement of the key, the spring 242 will immediately return the 95

40 lock sector to its right hand position and on the return movement of the slide bar the straight face 269 of the projection 267 will engage the lock sector and prevent return movement of the bar 24 and consequently 100

45 prevent return movement of the depressed key.

50 The attention of the operator is thus called to the fact that an error has been made. To release the depressed key it is merely necessary to press the disconnect lever which acting upon the arm 264 of the bell crank lever causes the other arm 265 to engage the cam 253, thereby moving the shaft 255 and all of the lock sectors to the 105

55 left sufficiently to release the projection 267

from the lock sector which has held it against return movement. The depressed key is therefore permitted to return to normal position and the error may be corrected at once. 110

When the lever 193 is rocked in the opposite direction the upward movement of the extension 266 engaging under the arm 243 of the bell crank lever will move the arm 246 of this lever in such manner as to disengage the jaw 249 from the frame 239 and thus break the connection between this frame and the locking sectors and also shifting them to the left. 115

Although subordinate to the parent case it is obvious that the invention may be regarded from different points of view and it is therefore to be considered as limited only by the scope of the appended claims. 120

I claim as my invention:

1. A combined typewriting and computing mechanism comprising a travelling totalizer, key operated means for entering numbers in said totalizer when it is in a certain zone, and error check mechanism rendered effective by the movement of the totalizer to a different zone which prevents the complete return movement of an incorrect key if depressed. 125

2. A combined typewriting and computing mechanism comprising a travelling totalizer, key operated means for entering numbers in said totalizer when it is in a certain zone, and error check mechanism rendered effective by the movement of the totalizer to a different zone which prevents the complete return movement of any key except those corresponding to the digits appearing in the total in said totalizer. 130

3. A combined typewriting and computing mechanism comprising a travelling totalizer, key operated means for entering numbers in said totalizer when it is in a certain zone, error check mechanism rendered effective by the movement of the totalizer to a different zone which prevents the complete return movement of an incorrect key if depressed, and means for releasing said key to permit its return to normal position. 135

4. A combined typewriting and computing mechanism comprising a travelling totalizer, key operated means for entering numbers in said totalizer when it is in a certain zone, error check mechanism rendered effective by the movement of the totalizer to a different zone which prevents the complete return movement of any key except those corresponding to the digits appearing in the total in said totalizer, and means for releasing said key to permit its return to normal position. 140

5. A combined typewriting and computing mechanism comprising a travelling register having column and grand totalizers, 145

- key operated means for entering numbers in either totalizer when it is in the computing zone, and error check mechanism which prevents complete return movement of an inaccurate key when the total appearing in the column totalizer is being entered into the grand totalizer.
6. A combined typewriting and computing mechanism comprising a travelling register having column and grand totalizers, key operated means for entering numbers in either totalizer when it is in the computing zone, error check mechanism which prevents complete return movement of an inaccurate key when the total appearing in the column totalizer is being entered into the grand totalizer, and manual means for releasing the key to permit its return to normal position.
7. A combined typewriting and computing mechanism comprising a travelling carriage, a travelling register having column and grand totalizers, key operated means for entering numbers in either totalizer when it is in the computing zone, error check mechanism automatically rendered operative by the movement of the register to bring the grand totalizer into the computing zone and preventing complete return movement of any incorrect key when depressed at this time, and means for releasing said key to permit it to return to normal position.
8. A combined typewriting and computing mechanism comprising a travelling register having column and grand totalizers, key operated means for entering numbers in either totalizer when it is in the computing zone, a series of auxiliary gears in said column totalizer, and means cooperating with said gears and acting to prevent complete return of an incorrectly depressed key when the grand totalizer is in the computing zone.
9. A combined typewriting and computing mechanism comprising a travelling register having column and grand totalizers, key operated means for entering numbers in either totalizer when it is in the computing zone, a series of auxiliary gears in said column totalizer, projections carried thereby, a member normally permitting complete return movement of a depressed key, and means cooperating with said projections to cause said member to prevent the complete return movement of an incorrect key when the grand totalizer is in the computing zone.
10. A combined typewriting and computing mechanism comprising a travelling register having column and grand totalizers, key operated means for entering numbers in either totalizer when it is in the computing zone, a series of members which normally permit complete return movement of any desired numeral key, and means automatically rendered effective by the movement of the register to bring the grand totalizer into the computing zone to prevent complete return movement of an incorrect key at this time.
11. A combined typewriting and computing mechanism comprising a travelling register having column and grand totalizers, key operated means for entering numbers in either totalizer when it is in the computing zone, a series of members which normally permit complete return movement of any desired numeral key, a series of auxiliary gears in the column totalizer, and means automatically rendered effective by the movement of the register to bring the grand totalizer into the computing zone and controlled by said auxiliary gears to prevent complete return movement of an incorrect key at this time.
12. A combined typewriting and computing mechanism comprising a travelling register having column and grand totalizers, key operated means for entering numbers in either totalizer when it is in the computing zone, a series of members which normally permit complete return movement of any desired numeral key, means automatically rendered effective by the movement of the register to bring the grand totalizer into the computing zone to prevent complete return movement of an incorrect key at this time, and manual means for releasing said preventing means.
13. A combined typewriting and computing mechanism comprising a travelling register having column and grand totalizers, key operated means for entering numbers in either totalizer when it is in the computing zone, a series of members which normally permit complete return movement of any depressed numeral key, a series of auxiliary gears in the column totalizer, means automatically rendered effective by the movement of the register to bring the grand totalizer into the computing zone and controlled by the auxiliary gears to prevent complete return movement of an incorrect key at this time, and manual means for releasing said preventing means.
14. A combined typewriting and computing machine comprising a series of slidable key actuated members, a series of lock sectors, an endwise movable shaft carrying said sectors, means for rocking said sectors upon the depression of the keys, and means for sliding said shaft endwise upon the actuation of an incorrect key.
15. A combined typewriting and computing machine comprising a series of slidable key actuated members, a series of lock sectors, an endwise movable shaft carrying said sectors, means for rocking said sectors upon the depression of the keys, and a cam upon each of said slidable members for sliding the shaft endwise upon the actuation of an incorrect key.

16. A combined typewriting and computing machine comprising a series of slidable key actuated members, a series of lock sectors, an endwise movable shaft carrying said sectors, means for rocking said sectors upon the depression of the keys, means for sliding said shaft endwise upon the actuation of an incorrect key, and manual means for sliding said shaft endwise.
17. A combined typewriting and computing machine comprising a series of slidable key actuated members, a series of lock sectors, an endwise movable shaft carrying said sectors, means for rocking said sectors upon the depression of the keys, a cam upon each of said slidable members for sliding the shaft endwise upon the actuation of an incorrect key, and manual means for sliding said shaft endwise.
18. A combined typewriting and computing mechanism comprising a travelling register including column and grand totalizers, a series of locking sectors, a rocking frame actuated upon the depression of a numeral key, and means for effecting an operative connection between the rocking frame and the locking sectors by the movement of the register to bring the grand totalizer into the computing zone.
19. A combined typewriting and computing mechanism comprising a travelling register including column and grand totalizers, a series of locking sectors, a rocking frame actuated upon the depression of a numeral key, means for effecting an operative connection between the rocking frame and the locking sectors by the movement of the register to bring the grand totalizer into the computing zone, and means whereby the locking sectors prevent return movement of an incorrect key at this time.
20. A combined typewriting and computing mechanism comprising a travelling register including column and grand totalizers, a series of locking sectors, a rocking frame actuated upon the depression of a numeral key, means for effecting an operative connection between the rocking frame and the locking sectors by the movement of the register to bring the grand totalizer into the computing zone, means whereby the locking sectors prevent return movement of an incorrect key at this time, and means for releasing said key from the locking sectors to permit complete return movement.
21. A combined typewriting and computing mechanism comprising a travelling register including column and grand totalizers, a rocking frame actuated by the depression of a numeral key, error check mechanism, and means controlled by the movement of the register to bring the grand totalizer into the computing zone for connecting the rocking frame to the error check mechanism.
22. A combined typewriting and computing mechanism comprising a travelling register including column and grand totalizers, a travelling carriage, a rocking frame actuated by the depression of a numeral key, error check mechanism, means controlled by the movement of the register to bring the grand totalizer into the computing zone for connecting the rocking frame to the error check mechanism, and means for breaking said connection.

In testimony whereof, I have hereunto subscribed my name.

GUSTAVE O. DEGENER.
